FIG. 2

FIG. 1 is a front perspective view of a cart carrier embodying our new design.

FIG. 2 is a front elevation thereof.

FIG. 3 is a side view thereof.

FIG. 4 is a bottom view thereof.

FIG. 5 is a top view thereof.

The broken lines indicating the cart and a portion of the truck on which the cart carrier is mounted are for illustrative purposes only.

The characteristic feature of our design resides in the horizontally disposed backturned cross angle and the pair of spaced-apart forwardly and then upwardly extending arm members for supporting the cart carrier.

We claim:

The ornamental design for a cart carrier, substantially as shown and described.
